(57) **CLAIM**

The ornamental design for a conference communication unit, as shown and described.

DESCRIPTION

FIG. 1 is a top plan view of a first embodiment conference communication unit showing my new design;

FIG. 2 is a rear elevation view of the conference communication unit of FIG. 1;

FIG. 3 is a left side elevation view of the conference communication unit of FIG. 1;

FIG. 4 is a right side elevation view of the conference communication unit of FIG. 1;

FIG. 5 is a bottom plan view of the conference communication unit of FIG. 1;

FIG. 6 is a bottom and front perspective view of the conference communication unit of FIG. 1;

FIG. 7 is a front and right perspective view of the conference communication unit of FIG. 1;

FIG. 8 is a top and right perspective view of the conference communication unit of FIG. 1;

FIG. 9 is a rear and right perspective view of the conference communication unit of FIG. 1;

FIG. 10 is a bottom and right view of the conference communication unit of FIG. 1;

FIG. 11 is a front view of the conference communication unit of FIG. 1 with a microphone attached to the unit; and,

FIG. 12 is a top plan view of a second embodiment of the conference communication unit showing my new design. The second embodiment is identical to the first embodiment except for the addition of the small circle shown on the middle of the conference communication unit.

Elements shown in broken lines in the drawings are for illustrative purposes only and do not form part of the claimed design.
